ABSTRACT OF THE DISCLOSURE

This invention relates to improvements in circuit breakers and more specifically to tilt-actuated circuit breakers, the contacts of which are caused to either make or break upon tilting of the circuit breaker carrier member, with respect to a reference plane, of the carrier member. Such a carrier member may include the landing gear truck of modern aircraft.

This application relates to a copending patent application entitled, "Improvements in Position Indicator Switches," by David Stewart, filed Nov. 23, 1966, and having U.S. Ser. No. 596,684.

Failure of many prior art circuit breaker switches to function properly occurs by short circuits arising from the accumulation of water within a supposedly air-tight or sealed switch case. Any air leak passageway into typical sealed switch cases acts as a water trap. Sources of such water traps are imperfect soldering techniques and the unpredictable life of the switch actuator shaft seal.

Later switch designs have abandoned the sealed or air tight approach and have introduced a vented case concept. This, too, has proved inefficient: the vent typically does not clean itself of dust particles and is open to water ingestion when the switch case is subject to water environments; insulation material used in many of the vented switch cases is water absorbent. Such insulation having absorbed water reduces electrical insulation, promotes tracking and causes switch contact arms to hang up.

It is an object of the teachings of this invention to provide a vehicle tilt-actuated switch having no life-limiting factors built into it. The switch is designed to last indefinitely, requiring only occasional cleaning and inspection.

A further object of the teachings of this invention is to provide a circuit breaker switch capable of handling contaminating environments to which it is subjected. Contaminants which ordinarily cause short circuit problems include water, cleaning solutions, and oil. A feature of the teachings of this invention provides that should such contaminants as sand or dust particles acquire entrance into the switch case, no failure of the switch to operate will occur.

A further object of the teachings of this invention is to provide means for eliminating, as far as possible, all bearings and pivots so that working parts will be as few and simple as possible.

Briefly, the teachings of this invention are directed to an improvement in vehicle position actuator level switches. The switch is essentially comprised of a plurality of movable electrical contact means such as two electrical contact arms, each carrying contact elements collectively comprising the plurality of contact means. The contact means are disposed to be actuated and be given movement relative to one another by an actuator means. More particularly, the contacts are supported upon the contact arms to rotate toward and away from each other about a supporting shaft. A ventilation assembly is provided in combination with container means which enclose the circuit

2

breaker or level switch. The vent assembly is provided for keeping the switch clean by allowing the passage of air therethrough and is constructed in the form of a labyrinth to prevent dust or foreign particles from reaching the switch contacts. Such a switch finds particular utility on the truck assembly of aircraft landing gear. The truck beam must bear a definite angle relationship to the landing gear strut or aircraft structure. Any tilting of the truck assembly will activate the switch of this invention to provide the pilot with a signal indication. The signal indication serves to advise the pilot when the truck assembly leveling mechanism has failed to work. In this case, danger exists that the aircraft wheels will catch on aircraft structure during landing gear retraction or lowering. Total failure of the landing gear to lock down could then occur and result in serious accidents.

This invention will appear more clearly from the following detailed description when taken in connection with the accompanying drawings, showing by way of example the preferred embodiment of the invention.

In the drawings:

FIGURE 1 is a cutaway perspective of a vehicle position or tilt-actuated level switch according to the teachings of this invention;

25 FIGURE 2 is an assembly detail of the actuator switch according to the teachings of this invention;

FIGURE 3 is a section view of the vehicle tilt-actuated level switch according to the teachings of this invention;

30 FIGURE 4 shows the movable electrical contact means wherein the contacts are separated from one another;

FIGURE 5 is a perspective section view of the vent assembly according to the teachings of this invention;

35 FIGURE 6A shows the movable electrical contact means having contact with one another;

FIGURE 6B shows the moveable electrical contact means just prior to contact with one another.

Referring to the drawings, FIGURE 1 shows a perspective view of a vehicle tilt-actuated level switch 10, according to the teachings of this invention. Metal casing means 12 and removable casing lid 12A enclose the switch mechanism described below in detail. Lid 12A is flanged over casing 12 to improve sealing capability. Electrical outlet 16 is attached to the casing means 12 by means (not shown) such as soldering. Electrical leads 15 interconnect the outlet 16 with movable contact arms or means 18. The electrical leads 15 are supported within casing 12 by bracket 13. Integrally connected to the contact means 18 are contact elements 20 and 21.

Continuing with reference to FIGURES 1 and 2, the electrical contact arms or means 18 are shown disposed for attachment to a pair of Delryn arms 25 by screws 19. The contact arms 18 are restrained in the position as shown in FIGURE 1 by means of spring 26 extensions 24 biasing against pins 47 which are fixedly attached to the Delryn arms 25. Spring 26 is so designed that under non-tilt conditions the extension 24 biases against the pins 47 so as to bring the contact arms 18, supported on the Delryn arms 25, into the position as shown in FIGURE 1, i.e., with physical contact existing between the semi-cylindrical contacts 20 and the cylindrical contact 21. By using two spring contact arms 18 instead of two pivoted levers, pivot friction or possible seizure at pivot points has been eliminated.

Continuing with reference to FIGURE 2, a rotatable shaft 32 is disposed within casing 12 and supported by a bushing 37, fixedly attached to casing 12, and a support bearing 36 integrally part of removable casing lid 12A. The rotatable shaft 32 is disposed for actuation by actuator means 31 which is fastened to shaft 32, once shaft 32 has been placed concentric within bushing 37, by a cotter pin 27 through a cotter pin hole 28 in shaft 32. The Delryn arms 25 with their associated contact arms 18 are

disposed axially about shaft 32 and positioned against support bearing or bushing 37 by a striker means 33 having a bushing 38 associated therewith. The striker 33 is fixedly attached to shaft 32 by a cotter pin 29 driven through an opening 30 in the bushing 38 which passes into an opening 30 in shaft 32. Thus, as actuator means 31, driven by a linkage (not shown) sensitive to tilting of switch 10 while supported upon a vehicle structure, rotates shaft 32, striker 33 is caused to rotate therewith. The spring 26 is fitted over bushing 38 of striker 33 and held thereon by bushing 34 which fits concentrically within spring 26. Bearing 36 is integrally cast to removable casing lid 12A which is tightened into position by bolts 45 shown in FIGURE 1.

Briefly in operation, separation of the contacts 20 and 21 occurs as follows. Upon vehicle tilting, actuator means 31 causes rotation of shaft 32 which drives striker 33 to bear against one of the pins 47, as seen in FIGURE 4, thus rotating one of the Delryn arms 25 about shaft 32. The other Delryn arm 25 is restrained from similar rotation by a fixed stop 49 which is fixedly attached to casing 12. Continued rotation of shaft 32 further loads the spring 26 until separation of contacts 20 and 21 is complete. As the vehicle (not shown), supporting switch 10, is returned to non-tilting position, shaft 32 is returned to its original position by actuator 31. Spring 26, free of influence of striker 33, returns the Delryn arms 25 to the position shown in FIGURE 3, i.e., with physical contact existing between contacts 20 and 21.

The switch 10 is therefore essentially comprised of: actuator means 31 responsive to change of vehicle position, and a plurality of movable electrical contacts, e.g., contacts 20 and 21, disposed to move relative to one another in a pivoting manner, supported by contact arms 18, about shaft 32, in response to the actuator means 31. The relative movement of the contacts 20 and 21 is such that when the vehicle tilts, i.e., shifts position relative to a reference plane, the contacts 20 and 21 move in a first direction relative to one another; when the vehicle is restored to its non-tilting position, the contacts 20 and 21 move in a second direction relative to one another and oppositely to said first direction. Whether movement of contacts 20 and 21 in a first direction results in making or breaking of physical contact between contacts 20 and 21 depends, of course, upon the initial mounting of switch 10 upon the supporting vehicle. As shown above in the preferred embodiments, switch 10 is mounted upon a supporting vehicle (not shown) such that contacts 20 and 21 are mated together, as seen in FIGURES 1 and 3, when the supporting vehicle is in its non-tilting position. Upon vehicle tilting, therefore, movement of contacts 20 and 21 in a first direction relative to one another will result in physical separation of contacts 20 and 21 to the condition as seen in FIGURE 4. Continuing, as the support vehicle is restored to its non-tilting position, movement of contacts 20 and 21 in a second direction relative to one another will result in physical contact or mating of contacts 20 and 21 again as seen in FIGURES 1 and 3.

Continuing with reference to FIGURES 3 and 4, contact 21 is cylindrical. Contacts 20 are semicylindrical, and otherwise are similar to contact 21.

With reference to FIGURES 6A and 6B, lower contact 20 and upper contact 20 have been given the reference letters A and B, respectively. The end portion 17a, of one of the contact arms 18 to which lower contact A is affixed, abuts against a mechanical stop 17b. End portion 17a and stop 17b serve as a second set of contacts. The contacts 20 (i.e., contacts A and B) are sprung toward each other by their respective contact arms 18; their minimum separation is fixed by adjustable stop 22 having an adjustment screw 23. It is assumed that synchronous contact between contact 21 and both contacts A and B is virtually impossible and that simultaneous contact by the entire length of either of the cylindrical contacts A and B with contact 21 is also impossible. It follows that as

the switch 10 makes or breaks, one end of one contact 20 (i.e., either A or B) will function. For illustration, assume that one end of upper contact B is the first and the last contact to function with contact 21. The make-break sequence will then be as follows: during the breaking cycle, the tip 17a of the lower contact A separates from the mechanical stop 17b against which 17a abuts as seen in FIGURE 6A. Continuing to FIGURE 6B, as upper contact B slides past contact 21, lower contact A will do so as well. After upper contact B has separated from contact 21, lower contact A separates and a spark is formed (assuming electrical current flows in leads 15 from a circuit and power source not shown). The point at which the spark is formed is not the normal conducting surface. As the contacts 20 and 21 make contact again, i.e., moving in a second direction relative to one another, the upper contact B will strike contact 21 first. It will do so at the point where contact was broken and where the contacts 20 and 21 are most liable to be contaminated. As upper contact B slides over contact 21, the spring arm 18 for upper contact B will deflect torsionally until contact along the length of cylindrical contact B and 21 is established. This length is not contaminated by the inductive spark which initially formed. As upper contact B continues to make contact with contact 21, it is raised upward by the cam action of the curvature of contact 21. This relieves the load on adjustable stop 22, and permits lower contact A to rise with its supporting arm 18 to make contact with 21. As relative movement continues, contacts 20 and 21 slide past each other with a wiping action. The line of contact on both contacts 20 and 21 continually changes. If it is desired to increase contact pressure, the tip 17a of lower contact A can be adjusted downward, causing it to ride along the top of the left Delryn arm 25 as shown in FIGURE 6A.

With reference to FIGURE 5, a switch 10 venting assembly or means 42 is shown attached to casing 12 by convenient means such as bolts 44. The vent assembly 42 comprises a metal baffle plate 46 and block of inert material 50 attached by bolts 44 to casing 12. A vent hole 48 passes through the baffle plate 46 and the casing 12. The piece of inert material 50, such as plastic or "Teflon," is aligned above the vent hole 48 in baffle plate 46 and held down with the baffle plate 46 to casing 12 by the bolts 44. Passageways 52 through the inert material 50 are provided allowing free air circulation through the vent hole 48 while preventing most solids such as dust particles and sand particles from entering the casing 12. For a dust particle to enter into the interior of casing 12, it would have to achieve four right-angle bends through the labyrinth passages 52 in the inert material 50. Since a dust or sand particle has mass and velocity, it is difficult to see why it should make even one bend through the labyrinth passages 52. Should it enter through the vent hole 48, it will encounter a fly-paper type of trap (not shown) within casing 12. The fly-paper trap consists of painting the inside of the casing 12 with a proper paint. The type of paint to be used will have the property of sticking to particles even when it is dry. This same paint is used as a gasket material for sealing the lid 12A (seen in FIGURE 1, attached by bolts 45 to casing 12). The paint dries enough to make a seal yet remains soft enough that the lid can be removed when desired. The bolts 45 are supported by sleeves 45A which are attached, as by welding, to casing 12. The bolts 45 pass through casing 12, within sleeves 45A, to fasten casing 12 and the switch 10 to a vehicle support structure in a given reference plane position, e.g., horizontal or vertical or some number of degrees from horizontal.

Thus, the labyrinth of means 42 provides for water or dust to easily leave the casing 12 but essentially prevents contaminants from entering the casing 12. The connector 16 is vented into the switch 10 so that no pressure difference exists between its internal air cavity and ambient.

Thus, the connector 16 will remain dry for the same reason as the switch 10 will remain dry.

With reference to FIGURES 3 through and including 6B, the preferred embodiment of switch 10 can be described with detail in operation. When the vehicle (not shown) to which switch 10 is attached shifts position relative to a reference plane, actuator means 31 will be driven to rotate clockwise or counterclockwise, depending upon the relative position shift of the support vehicle with respect to the reference plane. Shaft 32 will then rotate, with actuator means 31, within bushing 37 and bearing 36. Spring 26, not being fixedly attached to shaft 32, nevertheless tends to rotate with shaft 32 as striker 33, rotating with shaft 32, comes to drive against a pin 47 which serves to load spring 26. The spring 26 is prevented from rotating, however, by fixed stop 49, fixedly attached to casing 12, against which a Delryn arm 25 biases as it tends to rotate under the influence of spring extension 24 bearing against pin 47. Striker 33, rotating with shaft 32, continues to rotate the Delryn arm 25, attached to the pin 47 against which striker 33 bears, until the contacts 20, 21, 17a and 17b have moved in a first direction relative to one another and switch 10 appears as shown in FIGURE 4. This is the extreme position, however, and as is shown in FIGURE 6B, a signal can be established (by means of circuitry not shown) of pending dangerous shift of vehicle position relative to the reference plane at the moment tip 17a in FIGURE 6B breaks contact with its mechanical stop 17b on contact arm 18 so that vehicle leveling adjustment may be made before contacts 20 and 21 separate and the position as shown in FIGURE 4 is reached.

While in the foregoing there has been shown and described the preferred embodiment of this invention, it is to be understood that minor changes in the details of construction, combination and arrangement of parts may be resorted to without departing from the spirit and scope of the invention as claimed. Referring to FIGURE 4, for example, one might wish to mount switch 10, as shown, during non-tilting conditions. Then, as the vehicle (not shown) to which switch 10 is attached tilts (i.e., shifts position relative to a reference plane) actuator means 31 will cause striker 33 to unload spring 26. In this manner a signal will be established of pending dangerous vehicle tilt conditions when contacts 17a, 17b, 20 and 21 move in a first direction relative to one another which is opposite the first direction of movement described in the above preferred embodiment. In other words, the contacts 17a, 17b, 20 and 21 move so as to make contact and vehicle leveling adjustment is made before contacts 20 and 21 move together.

I claim:

1. A vehicle position actuated switch comprising:
  - (a) actuator means responsive to changes of vehicle position between a tilt and a non-tilt condition;
  - (b) a first moveable electrical contact having a substantially cylindrical contact surface;
  - (c) a pair of second moveable electrical contacts each having opposed substantially cylindrical contact surfaces yieldingly spaced apart and adapted to receive said first electrical contact therebetween; and
  - (d) linkage means connected between said actuator means and said first and second electrical contacts for moving said first and second electrical contacts relative to each other in response to said actuator means between a closed position, wherein said first electrical contact is interposingly engaged between and in substantially line contact with each of said pair of second electrical contacts, and an open position, wherein said first electrical contact is disengaged from said second pair of electrical contacts.
2. The vehicle position actuated switch as claimed in claim 1 wherein said linkage means comprises:
  - (a) spring means for normally biasing said first and second electrical contacts in one position; and

- (b) striker means connected to said actuator means for moving said first and second electrical contacts against the bias of said spring means to the other position.
3. A vehicle position actuated switch comprising:
  - (a) actuator means responsive to change of vehicle position between a tilt and a non-tilt condition;
  - (b) a pair of moveable contact arms made of electrical insulating material;
  - (c) a first electrical contact carried by one of said contact arms, said contact having a substantially cylindrical contact surface;
  - (d) a pair of second electrical contacts yieldingly carried by the other of said contact arms in spaced apart relationship, each of said second electrical contacts having opposed substantially cylindrical contact surfaces adapted to receive said first electrical contact therebetween;
  - (e) spring means normally biasing said pair of contact arms to a closed position wherein said first electrical contact is interposed between and engaged in substantially line contact with each of said pair of second electrical contacts; and
  - (f) striker means operatively associated with said actuator means, said striker means engaging at least one of said pair of contact arms to position said contact arms in an open position against the bias of said spring means wherein said first electrical contact is disengaged from said second pair of electrical contacts.
4. A position actuated electrical switch comprising:
  - (a) rotatable shaft means for rotation by an actuator;
  - (b) a pair of contact arms each mounted rotatably about said shaft means and made of electrical insulating material;
  - (c) a first electrical contact carried by one of said contact arms, said contact having a substantially cylindrical contact surface;
  - (d) a pair of second electrical contacts yieldingly carried by the other of said contact arms in spaced apart relationship, each of said second electrical contacts having opposed substantially cylindrical contact surfaces adapted to receive said first electrical contact therebetween;
  - (e) spring means normally biasing said pair of contact arms to a closed position wherein said first electrical contact is interposed between and engaged in substantially line contact with each of said pair of second electrical contacts; and
  - (f) striker means attached to said shaft means for rotation therewith, said striker means engaging said pair of contact arms to rotate said contact arms to an open position against the bias of said spring means wherein said first electrical contact is disengaged from said second pair of electrical contacts.
